UNITED STATES PATENT OFFICE

TOM R. STUART, OF WASHINGTON, DISTRICT OF COLUMBIA, ASSIGNOR TO
THE EAGLE PENCIL COMPANY, OF NEW YORK, N. Y.

PEN-HOLDER.

SPECIFICATION forming part of Letters Patent No. 400,368, dated March 26, 1889:

Application filed January 12, 1889; Serial No. 296,200. (No model.)

To all whom it may concern:

Be it known that I, TOM R. STUART, of Washington city, in the District of Columbia, have invented a certain new and useful Improvement in Pen-Holders, of which the following is a specification.

My invention is directed to obtaining a cheap and efficient pen-holder which can easily be manipulated to effect the insertion or removal of the pen.

I am aware that various devices have heretofore been devised or suggested for the purpose of ejecting pens from pen-holders, and that for the same purpose the one part of the pen-holder has been arranged to slide upon the other, and in some instances the inner part has been arranged as a spring, which might be pushed inwardly away from the outer part, so as to open the pen-slot and thus allow the pen to drop out.

My invention differs from all others of which I have knowledge in that the external part of that portion of the pen-holder which receives the pen is hinged or pivoted at or near the front to the body of the holder, so that it may be tilted with reference to said body to permit the insertion or removal of the pen. By placing the hinge in the position indicated the pressure exercised upon the pen when in ordinary use for writing purposes has no lifting effect upon the hinged part, but, indeed, tends, if anything, to hold it down in place. I can, however, and in practice do, provide the hinged part at the rear with one or more spring catches or ears, which, when the said hinged part is turned down, snap over some portion of the body of the pen-holder, and thus secure the hinged part in place.

The nature of my invention and the manner in which the same is or may be carried into effect will be readily understood by reference to the accompanying drawings, in which—

Figure 1 is a side elevation of my improved holder with the pen inserted and ready for use. Fig. 2 is a side elevation of the same, with the hinged part raised or tilted and the pen in the position it occupies when being either placed in or taken from the holder.

Fig. 3 is a front view of the holder. Fig. 4 is a section on line 4 4, Fig. 1.

In the figures, C is the external hinged part of the holder, and b is the co-operating inner part, between which and said hinged part is formed the slot e for insertion of the pen.

In the particular structure shown in the drawings the tenon a on the point end of the pen-handle A provides the inner portion of the holder, between which and the outer barrel the pen is to be inserted, and this tenon is preferably surrounded by the metallic sleeve b. The outer barrel of the holder surrounds the sleeve b, and is divided longitudinally into two halves—one, B, of which is fastened to the sleeve b, and the other, C, of which is hinged at or near its front by pivot-pins c, which pass through ears d on the hinged part C, through the part B and sleeve b, and into the wooden tenon, as indicated in Fig. 3. The pen-slot or slot for insertion of the pen is at e, Fig. 3, between the inner surface of hinged part A and the opposite outer surface of the part b.

Spring-ears f are provided on the rear portion of the hinged part C, which, when the said part is turned down into place, extend below the longitudinal center of the barrel and snap or close round said barrel, as seen in Fig. 4, so as to secure the hinged part in place. For these ears any other suitable fastening device can be substituted. Such a device will generally be desirable, but is not indispensable, because the arrangement is such that the pressure upon the pen when used for writing will not tend to raise the hinged part, but will, if anything, tend to hold it down, and this tendency can be increased, if desired, by moving the pivoted or hinged point c a little back from the front end of the holder, as indicated by dotted lines at e', Fig. 1.

The manner in which the pen-holder can be used and manipulated is indicated so fully in Figs. 1 and 2 as to require no further description.

Manifestly the part B can be dispensed with; so, also, can sleeve b, and the construction of the holder can obviously be varied otherwise. What is essential is that there

should be an inner part, *b*, between which and the outer part, *A*, is formed the pen-slot *e*, and that the outer part, *A*, should be hinged at or near its front end, so as to be capable of tilting longitudinally with reference to said inner part, *b*, substantially in the manner hereinbefore indicated.

What I claim herein as new and of my own invention, and desire to secure by Letters Patent, is as follows:

1. A pen-holder having an inner part, *b*, and an outer part, *C*, between which two parts is the pen-slot *e*, said outer part, *C*, being hinged or pivoted at or near its front end to the body of the holder, so as to be capable of

tilting longitudinally with reference to the part *a*, as hereinbefore shown and described.

2. The combination, with the inner part, *b*, of the holder, of the outer part, *C*, hinged to the body of the holder at or near its front end and provided with a spring fastening device by which when it is turned down it is secured to the body of the holder, as set forth.

In testimony whereof I have hereunto set my hand this 9th of January, 1889.

TOM R. STUART.
